Whitma Louise De Courcey Inventor

By G. H. Audley, Jr. Attorney

UNITED STATES PATENT OFFICE.

WHILMA LOUISE DE COURCEY, OF BUFFALO, NEW YORK.

PROTECTOR.

1,254,483.

Specification of Letters Patent. Patented Jan. 22, 1918.

Application filed October 23, 1915. Serial No. 57,601.

To all whom it may concern:

Be it known that I, WHILMA LOUISE DE COURCEY, a subject of the King of Great Britain, residing at Buffalo, in the county 5 of Erie and State of New York, have invented certain new and useful Improvements in Protectors; and I do hereby declare the following to be a full, clear, and exact description of the invention, such as will 10 enable others skilled in the art to which it appertains to make and use the same.

The primary object of the invention is to provide a protector for soldiers to be worn under the waist coat and formed of such material as to practically render the same bullet proof, and also to protect the wearer from cold.

A further object of the invention is to provide a protector for carrying out the above 20 object, which can be manufactured cheaply, can be adjusted to accommodate different size persons and will be durable and efficient in use, and can be comfortably worn.

Other objects will appear and be better 25 understood from that embodiment of my invention of which the following is a specification, reference being had to the accompanying drawings forming a part thereof, in which:

30 Figure 1 is a front view of the protector,
Fig. 2 is a side view thereof,
Fig. 3 is a front view of the inner jacket, and
Fig. 4 is a detail section taken through

35 Fig. 2.
Referring to the drawing, the letter A designates the protector as an entirety, and which comprises an outer section 1 formed of steel, and an inner section 2, said inner 40 section being formed of layers of leather and flannel 3 and 4. The inner section having arm holes 4' therein, the forward side of the inner section being formed of overlapping portions 5—5 adapted to overlap the 45 chest of the wearer and to be adjustably connected by means of straps 6.

The outer section 1 includes a front portion 7 and a rear portion 8. The portions 7 and 8 are adapted, respectively, to lie over 50 the chest and back of the wearer and each is of such length as to extend from the neck to the waist of the wearer, and are transversely curved to agree with the curvature

of the body of the wearer. The upper edge of each portion 7 and 8 is cut out on a 55 curved line 9 to provide a neck opening and each portion has its upper end provided with curved extensions 10 and 11, which are adapted to engage over the shoulders of the wearer, and are adjustably connected to each other by means of straps 12. Each of the portions 7 and 8 has side extensions 13 formed thereon, which engage around the sides of the body of the wearer and are provided with vertical rows of openings 14. 60 Adjacent opposed side extensions 13 are connected to each other by means of a lacing 15, which is threaded through the openings 14 in the opposed extensions 13, and adjustably connects the extensions to each other. The 65 upper ends of the side extensions 13 terminate a considerable distance below the neck opening of the protector and have their upper ends gradually merging, as at 16, into the adjacent side edges of the adjacent 70 curved extensions 10 and 11 and form with the extensions 10 and 11 arm holes 17.

The lower ends of the portions 7 and 8 have mounted thereon, at spaced points, belt loops 18 for the reception of a belt 19. This 80 belt 19 is provided with spaced pockets 20 closed by flaps 21, the said pockets being particularly adapted to receive ammunition.

What I claim as new is:

1. A protector of the class described including an inner section formed of leather and having a layer of flannel on the inner surface thereof, flaps forming the front of the inner section and adapted to overlap each other, means for adjustably connecting 85 the flaps, and a metallic section fitted over the inner section. 90

2. A protector of the class described including an inner section formed of leather and having a layer of flannel on the inner 95 surface thereof, flaps forming the front of the inner section and adapted to overlap each other, means for adjustably connecting the flaps, and an outer adjustable metallic section fitted over the inner section. 100

In testimony whereof I affix my signature in presence of two witnesses.

WHILMA LOUISE DE COURCEY.

Witnesses:

CORNELIA A. BEALS,
PASCAL P. BEALS.
